CLAIM

The ornamental design for an armrest for car or truck, as shown and described.

DESCRIPTION

FIG. 1 is a front elevation view of an armrest for car or truck showing my new design, with the rear elevation view being a mirror image thereof;

FIG. 2 is a left side elevation view thereof;

FIG. 3 is a right side elevation view thereof;

FIG. 4 is a bottom plan view thereof;

FIG. 5 is a top plan view thereof; and,

FIG. 6 is an isometric view thereof.

The broken lines in the drawings illustrate portions of the armrest which form no part of the claimed design. The broken lines depicted on the top and bottom surfaces of the armrest depict stitching, which forms no part of the claimed design.
